The ornamental design for a display screen with animated graphical user interface, as shown and described.

DESCRIPTION

1. Display screen with animated graphical user interface

1.1 : Front

1.2 : Front

1.3 : Front

1.4 : Front

The appearance of the transitional image sequentially transitions between the images shown in FIGS. 1.1 to 1.4. The process or period in which one image transitions to another image forms no part of the claimed design. Reproduction 1.1 is the figure showing the state before change; and reproductions 1.2-1.4 are the figures showing the state after change; the broken lines depict portions of the display screen with animated graphical user interface that form no part of the claimed design.
